UNITED STATES PATENT OFFICE.

JAMES F. BOGGS, OF NEEDLES, CALIFORNIA.

CLOTH MEASURING AND MARKING MACHINE.

No. 813,767.

Specification of Letters Patent.

Patented Feb. 27, 1906.

Application filed September 26, 1905. Serial No. 280,215.

To all whom it may concern:

Be it known that I, JAMES F. BOGGS, a citizen of the United States, residing at Needles, in the county of San Bernardino and State of California, have invented a new and useful Cloth Measuring and Marking Machine, of which the following is a specification.

This invention relates to machines for measuring flexible material, such as textiles and the like, and for simultaneously marking the material measured at predetermined intervals to indicate the quantity of material in a piece or the length of such piece.

Among the objects of the invention are to simplify and improve the construction and operation of this class of devices; and with these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that changes, alterations, and modifications within the scope of the invention may be resorted to whenever desired.

In the drawings, Figure 1 is a side elevation, partly in section, of a machine constructed in accordance with the principles of the invention. Fig. 2 is a top plan view of the same. Fig. 3 is a sectional detail view taken on the plane indicated by the line 3 3 in Fig. 1. Fig. 4 is a detail view showing in side elevation the marking wheel or disk in connection with tagging mechanism co-operating therewith. Fig. 5 is a detail plan view, partly in section, of the tagging mechanism. Fig. 6 is a detail plan view illustrating a modified form of marking mechanism. Fig. 7 is a detail elevation, partly in section, of said modified form of marking mechanism. Fig. 8 is a detail view illustrating a modification.

Corresponding parts in the several figures are indicated by like characters of reference.

The device of this invention is preferably supported upon a base comprising a rectangular frame 1, provided at the corners thereof with legs or supporting members 2 2. Said frame is provided near the ends thereof with

means for supporting for rotation devices, such as flat boards 3 3, constituting the reels, from and upon which the material which is to be measured and marked is unwound and wound. These boards or reels are supported for rotation by means, such as pintles 4, which extend through perforations in the sides of the frame and the inner pointed ends of which may be placed in engagement with the edges of the boards 3, said pintles being held in position by means such as set-screws 5. The opposite ends of the boards are supported by means such as spring-actuated clutch members 6 and 7, supported for rotation in the opposite side of the frame, the member 7 being provided with a crank or handle 8, whereby it may be manipulated for the purpose of winding material upon the board or reel connected therewith.

Upon the sides of the main frame 1 are supported upright frames 9 and 10, having bearings for a shaft 11, carrying a roller 12, upon which is adjustably supported the hub 13 of a measuring wheel or disk 14, said hub being secured by means of a set-screw 15, which admits of the hub being secured in various positions upon the roller. The sides of the frame 1 are provided with bearings for a shaft 16, carrying a pressure-roller 17, the periphery of which is almost in contact with the rim or periphery of the measuring-wheel 14. The perimeter of the measuring-wheel is of predetermined dimensions—say one yard in circumference—so that each rotation of said wheel will denote the passage of one yard of material between said measuring-wheel and the pressure-roller 17. The latter or the measuring-wheel, or both, may have surfaces covered or coated with rubber or otherwise prepared to insure the regular rotation of said wheel and roller by the passage therebetween of material, such as indicated at 18, when said material is unwound from the board at one end of the machine and wound upon the board at the opposite end.

Upon the frame 10, which supports the front end of the shaft 11, is fulcrumed a lever 19, one end of which lies in the path of a cam 20, secured upon the shaft 11, and the opposite end of which carries a pin or stud 21, upon which a marking-wheel 22 is supported for rotation. Said marking-wheel is provided upon its rim or periphery with type, as 23, disposed at equidistant intervals, said type consisting of numbers arranged in nu-

merical order from 1 upward. In the example shown in the drawings the type-wheel or marking-wheel is composed of a disk 24, having laterally-extending lugs 25 formed integrally therewith, said lugs being spaced apart by slots 26. A spring-pawl 27 is supported upon the frame 1 in a position to engage the notches or slots 26 between the type-bearing lugs 25. A spring 28, arranged within a casing 29, which is pivotally connected with the lever 19, serves to normally force the wheel-bearing end of said lever in an upward direction to hold the marking-wheel free from contact with the subjacent parts, which will be presently described.

Supported upon one of the side members of the frame 1, directly beneath the marking-wheel, is a casing 30, which includes a trough or basin 31 and side members 32, that afford bearings for a roller 33, carrying a roll of paper 34 and a pair of coöperating feed-rollers 35 and 36, the former of which is partly submerged in the trough 31, said rollers 35 and 36 coöperating to engage the strip of paper coming from the roll 34. The lower feed-roller 35 is driven by means of a round belt or cord 37, engaging a groove 38 in the shaft 16 and passing from thence over a pair of approximately horizontal idlers 39, over a grooved pulley 40 upon the shaft of the roller 35, the roller 36 being operated by frictional contact with the material passing between the two rollers. If preferred, the rollers may be geared together to constitute a positive feed, as illustrated in the detail view, Fig. 8 of the drawings, where 41 and 42 designate the intermeshing gears.

Upon the side of the frame 1 directly adjacent to the casing 30 is supported a platen 43, having a shoulder or offset 44, which is adapted for coöperation with a cutter 45, which is secured upon the lever 19, with which it is partly connected by means of the pin or bolt 21, which constitutes the axis of the marking-wheel. The said pin or bolt also carries a pivoted freely - swinging member 46, which is supported closely adjacent to the cutter 45 and which is provided at its lower end with a presser-foot 47. The cutter 45, as will be best seen in Fig. 4 of the drawings, is provided with a lug 48, which lies in the path of the pivoted member 46 and prevents the latter from swinging beyond said lug in the direction of the measuring-wheel, 55 while the swinging movement of the member 46 in the opposite direction is unobstructed.

The trough 31, in which the roller 35 is partially submerged, contains adhesive material, which is applied by said roller to the under side of the paper strip coming from the roll 34, or said paper strip may have been previously coated with adhesive material, in which event the contents of the trough 31 will simply be water for the purpose of moistening said adhesive material.

The frame 1 adjacent to the marking-wheels supports an inking device (conventionally indicated at 49) for the purpose of inking the type upon the marking-wheel.

The operation of the invention as thus far set forth will be readily understood from the foregoing description, taken in connection with the drawings. The material which is to be measured is passed from the unwinding reel or board between the measuring-wheel 75 and the pressure-roller, care being taken to previously adjust the marking-wheel so that the numeral 1 will be the first one brought into action. As the material advances under the measuring-wheel one complete rotation of the latter brings about the tripping of the lever 19, carrying the marking-wheel, with the result of depressing said marking-wheel, thus imprinting a number on the strip of paper underneath and causing the cutter 85 45 to sever the previously-printed portion of the strip which overhangs the edge of the fabric that passes beneath the presser-foot 47. The latter being simultaneously depressed serves to press the numbered strip or tag 90 which is severed by the cutter 45 into contact with the fabric, to which it is caused to adhere by the adhesive substance with which it is coated, the presser-foot swinging clear of the fabric, as shown in Fig. 4, as the latter advances in the direction of the board or reel upon which it is being wound. Each yard or predetermined measurement of the material is thus measured and numbered with absolute certainty, the marking-wheel being advanced one step at each operation by the action of the spring-pawl 27 engaging the same.

It will be observed that the movement of the marking-wheel is practically instantaneous and is extremely limited, so that it will 105 not obstruct the feed mechanism whereby the paper-roll is being advanced. Said feed mechanism will be obviously adjusted to feed the paper at the desired rate of speed.

Under some circumstances, and especially 110 when light-colored material is being wound and measured, it may be found desirable to imprint the mark or number directly upon the fabric itself instead of utilizing a strip or tag of paper. When this modification is 115 adopted, as illustrated in Figs. 6 and 7 of the drawings, the paper-roll and the feeding and pasting devices are dispensed with and the marking-wheel is supported directly above the strip of material which passes over the 120 platen 43, the inking mechanism being obviously supported in such a position as to apply ink to the periphery of the wheel, which at each operation is caused to imprint a number upon the edge of the fabric.

This improved device, as will be readily seen, is extremely simple in construction, as well as efficient in operation. An important feature of the invention is that material wound and marked by this device always 125 130

shows precisely the quantity that is left in a piece no matter how much may have been separated therefrom, thus saving much labor in rewinding and measuring material at stock-taking time. The improved machine, it will be observed, will operate with equal efficiency upon materials of various widths, even quite narrow strips, since the winding and unwinding boards, as well as the measuring-wheel, may be adjusted as closely as may be desired to the front side of the frame which supports the marking mechanism.

Having thus described the invention, what is claimed is—

- 15 1. In a machine of the class described, a measuring-wheel, a cam upon the axis of said wheel, a lever having an end extended into the path of said cam, a spring supporting the opposite end of the lever, a marking-wheel supported for rotation upon said lever, and a spring-pawl supported in constant engagement with notches in the said marking-wheel.
- 20 2. A measuring-wheel, a cam upon the axis of said wheel, a lever having an end extended into the path of said cam to be operated thereby, a spring supporting the lever on the opposite side of its fulcrum, a marking-wheel supported for rotation upon the spring-supported end of the lever, said wheel being provided with spaced type-carrying lugs, and a spring-pawl supported in constant engagement with the lugs and the spaces therebetween.
- 25 3. A measuring-wheel, a lever supported in the path of and adapted to be tripped by means connected with the measuring-wheel, a marking-wheel supported for rotation by the lever, means for advancing said marking-wheel one step at each operation of the lever, a platen beneath the marking-wheel, and means for advancing an adhesive-coated

strip between the marking-wheel and the platen.

4. A vibratory lever, a marking-wheel supported for rotation upon the said lever, a 45 platen beneath said marking-wheel, means for advancing the latter one step at each vibration of the supporting-lever, means for advancing an adhesive-coated strip between the platen and the marking-wheel, and cutting means connected with the lever adjacent to the marking-wheel.

5. A marking-wheel, a vibratory lever supporting said wheel, means for advancing the marking-wheel one step at each vibration of 55 the supporting-lever, a platen supported beneath the wheel having a shoulder or offset, means for applying ink to the face of the wheel, means for advancing an adhesive-coated strip between the wheel and the platen, 60 and a cutter connected with the lever adjacent to the wheel and coöperating with the shoulder of the platen to sever the portion of the strip advanced beyond the wheel when the latter is depressed.

6. A marking-wheel, a vibratory lever supporting said wheel, a shouldered platen beneath said wheel, means for applying ink to the face of the wheel, means for advancing an adhesive-coated strip between the wheel 70 and the platen, a cutter connected with the lever and coöperating with the shouldered platen, and a member pivoted adjacent to the cutter and terminating at its free end in a presser-foot.

In testimony that I claim the foregoing as my own I have hereto affixed my signature in the presence of two witnesses.

JAMES F. BOGGS.
